UNITED STATES PATENT OFFICE.

SIDNEY ROSENFELD, OF CLEVELAND, OHIO.

COMBINED BUNG AND FAUCET.

1,190,802.

Specification of Letters Patent. Patented July 11, 1916.

Application filed August 15, 1914. Serial No. 856,921.

To all whom it may concern:

Be it known that I, SIDNEY ROSENFELD, a citizen of the United States, residing at Cleveland, in the county of Cuyahoga and State of Ohio, have invented a certain new and useful Improvement in Combined Bungs and Faucets, of which the following is a full, clear, and exact description, reference being had to the accompanying drawings.

This invention relates to so called "reversible faucets" for barrels or other receptacle, and has for its object to provide an attachment whereby a reversible faucet can be conveniently secured in place, both during the period occupied in the shipment of the barrel to the consignee and during the period occupied in removing the contents from the barrel.

It is the general object of the invention to provide a connection of the character referred to which, while extremely simple and economical of production, is equally efficient in operation; one which will maintain a tight joint at all times between the base or plug of the faucet and the connecting bushing; and one which, while employing a modified form of such bushing, will enable practically the entire contents of the barrel to be removed when the barrel is turned to an upright position; also a construction which will secure this result and at the same time enable the parts, during shipment, to be located within and protected by the chime of the barrel.

In the drawings forming part hereof Figure 1 represents a sectional detail through the head of a barrel showing a faucet applied thereto; Fig. 2 a similar view showing the faucet reversed, for shipment of the barrel.

Describing by reference characters the various parts illustrated herein, 1 denotes the external shell and 2 one of the heads of a barrel (or similar receptacle) the barrel being preferably of metal and having the head united to the end of the barrel body in and through a flange, the flange in this case being formed by bending the metal of the head, adjacent its periphery, upon itself, as shown at 3, and inserting between the metal parts, the cylindrical end 4 of the body. The parts may then be united in any desired manner. The head is shown as provided

with a cylindrical aperture for the bushing. 55 This bushing is fastened therein in any suitable manner and comprises a cylindrical body 5 having at one end a radially extending flange 6, which may be beveled, as shown at 6^a. At its opposite end, the bushing is 60 provided with an inwardly projecting radial flange 7, the body of the bushing being provided with an internal thread 8 and the flange being of less internal diameter than the internal diameter of the threaded part 65 of the bushing whereby a retaining wall or flange is provided for a packing ring 9.

In order to secure the removal of practically all of the contents of the barrel when it stands upright, the metal surrounding the 70 aperture for the bushing is pressed outwardly, as shown at 2^a, to provide an annular corrugation having a flat seat for the adjacent face of the bushing flange 6. The metal will be pressed outwardly a sufficient 75 distance to bring the inner surface of the bushing substantially flush with the inner surface of the barrel head, and the parts will be so proportioned that, when thus assembled, the outer surface of the bushing 80 will be well within the outer edge of the chime.

10 denotes the body of the faucet, said body being provided with an externally threaded base 11 which is of such diameter 85 as to be threaded into the threaded portion 8 of the bushing. On opposite sides of the base 11 angular projections 12 and 13 are provided for the application of a wrench. The projection 12 is hollow and provides an 90 inlet extension for the faucet when placed in position to empty the barrel. When the faucet is placed within the barrel (for shipment) the projection 12 is provided with a plug 12^a which is removed when the faucet 95 is reversed for the purpose of emptying the barrel. This projection in effect extends the plug 12 by the length of the projection and to that extent would prevent completely emptying the receptacle but for the particular arrangement of parts shown herein.

It is believed that the operation will be apparent from the foregoing description and an inspection of the drawings. Prior to use and to facilitate shipping, the bung 105 will be applied to the barrel in the manner shown in Fig. 2, with the plug 12^a in place, the base being screwed into the threaded

- part 8 of the bushing and compressing the washer or packing ring 9 against the flange 7. When it is desired to remove the contents of the barrel, the faucet will be unscrewed and reversed and its base will be again threaded into the bushing, the flange 7 and packing ring 9 serving in both instances to form a tight joint with the aforesaid base and to prevent any leakage.
- 10 As will be evident from the drawing, the conveyer and faucet base will be protected during the shipment of the barrel.

Owing to the arrangement of the bushing with reference to the head of the barrel, it 15 will be evident that the contents of the barrel when it is upright may be removed without any hindrance by the bushing, since the latter does not project inwardly beyond the inner surface of the barrel head.

Having thus described my invention, what 20 I claim is:—

The combination of a bushing threaded internally and having an outwardly projecting attaching flange at one end, and an inwardly projecting flange at its other end, 25 beyond the threaded portion, a reversible faucet having an outwardly projecting base the rim of which is threaded its whole width, whereby said threads may be screwed into the bushing in either direction, and 30 backing between said base and said inwardly projecting flange.

In testimony whereof, I hereunto affix my signature in the presence of two witnesses.

SIDNEY ROSENFIELD.
